UNITED STATES PATENT OFFICE

WILLIS S. SHAFT, OF FARIBAULT, MINNESOTA

SPRING HEEL SEAT

Application filed June 23, 1931. Serial No. 546,335.

This invention appertains to foot wear and more particularly to novel means for cushioning the heel of a shoe to prevent the transmission of shock to the wearer of the shoe incident to walking, and is an improvement over my prior Patent No. 1,766,311, issued to me June 24, 1930.

One of the primary objects of my present invention is the provision of a novel heel piece having a cushioning pad extending therethrough, the heel piece being adapted to be placed between the outer sole and a combination middle and inner sole so that the cushioning pad will effectively engage 10 the adjacent faces of the combination middle and inner sole and the outer and thereby form an effective cushioning support for the heel of the wearer; the heel piece itself functioning to form an effective support for 15 the entire heel of the wearer.

Another important object of my invention is the provision of novel means for forming the combination middle and inner sole for receiving the upper end of the cushioning 20 pad so as to permit the maximum amount of benefit to be obtained from the cushioning pad with a minimum amount of material between the pad and the heel of the wearer.

Another salient object of my invention is 25 the provision of a resilient heel piece adapted to be permanently placed between the combination middle and inner sole and outer sole of a shoe, the resilient heel piece carrying a cushioning pad so disposed and arranged as to form an effective cushioning support for the calcaneum bone of a foot 30 of the wearer of the shoe.

A still further object of my invention is 35 to provide a cushion heel support or pocket for the calcaneum bone to rest in when walking, of the above character, which will be durable and efficient in use, one that will be simple and easy to manufacture, and one 40 which can be incorporated with a conventional shoe at a low cost.

With these and other objects in view, the invention consists in the novel construction, arrangement and formation of parts, as will 45 be hereinafter more specifically described,

claimed, and illustrated in the accompanying drawing, in which drawing:—

Figure 1 is a top plan view of a shoe sole with my improved heel seat incorporated therewith, the combination middle and inner sole being turned back to illustrate the cavity formed in the lower face thereof for receiving the resilient pad or ball of the cushion heel piece.

Figure 2 is a longitudinal section through the shoe sole constructed in accordance with my invention showing the cushion heel piece cemented or otherwise fastened to the upper face of the outer sole and the combination middle and inner sole partially cemented 60 to the outer sole.

Figure 3 is a transverse section taken on the line 3—3 of Figure 2.

Figure 4 is a longitudinal section through a sole showing a slightly modified form of 70 my invention.

Figure 5 is a view similar to Figure 1 illustrating the slightly modified form of my invention shown in Figure 4, and

Figure 6 is a detail fragmentary perspective view of the heel piece carrying the 75 resilient pad.

Referring to the drawing in detail, wherein similar reference characters designate corresponding parts throughout the several 80 views, the letter A generally indicates a shoe sole constructed in accordance with my invention and as shown the shoe sole A embodies a combination middle and inner sole 85 and an outer sole 11.

The combination middle and inner sole 10 is treated in the ordinary way to receive the lining and upper of the shoe and in accordance with my invention the heel portion 12 thereof has lower face provided 90 with a recess 13, leaving a relatively thin section of leather 14 at the central heel portion thereof.

One of the salient features of my invention is the provision of the cushion heel 95 piece 15 which is shaped to conform to the construction or configuration of the heel portions of the combination middle and inner sole 10 and outer sole 11 and the body portion of the cushion heel piece 15 can be 100

constructed from leather if preferred, and the forward transverse edge thereof is beveled as at 16 so as to make a smooth junction with the shank of the soles. The central portion of the body of the cushion heel piece 15 is provided with an opening 17 in which is received a pad of resilient material 18, which is preferably formed of sponge rubber. While I have particularly designated sponge rubber for the resilient pad and leather for the body portion of the heel piece, it is to be understood that these materials can be changed and still come within the scope of the invention, as I can use other resilient material instead of sponge rubber and other material instead of leather for the body portion of the heel piece. This pad of resilient material 18 preferably extends above and below the opposite faces of the heel piece and the upper projecting portion of the resilient pad is received within the cavity 13 of the heel portion 12 of the middle sole 10. These parts are all cemented or otherwise fastened together in the finished sole, so as to form a substantially unitary article.

The shape of the resilient pad 18 can be widely varied and in Figures 1 to 3 inclusive I have shown the pad of a circular shape.

In Figures 4, 5, and 6, I have shown this pad of a shape to conform to the usual configuration of a shoe heel and the pad in Figures 4 to 6 inclusive is indicated by the reference character 20. It is to be noted that the pad in this modified form also extends materially above and below the opposite faces of the heel piece 15 and while I have specified that the combination middle and inner sole and the outer sole are cemented together, it is to be understood that the same can be also sewed together.

By my improved construction the cushion heel can be readily incorporated in the shoe during the course of manufacture thereof and the heel piece 15 forms an admirable way of carrying the cushioning pad and to permit the same to be readily incorporated in the shoe. Further the heel piece itself forms a heel support and insures the proper cushioning of the heel of the wearer at the desired point. The provision of the cavity 13 not only prevents the displacement of the pad of cushioning material but also defines a relatively thin piece of leather between the cushion pad and the heel of the wearer so as to permit the wearer to obtain a maximum amount of benefit from the cushioning pad. Further the thin piece of

material 14 is of a relatively flexible nature due to the thinness thereof and thus will not cause any discomfort to the wearer, and will effectually prevent what is termed by orthopedists as "oscillating or rotating heel" 70 bones" which is the direct cause of distorted heel seats in spring heel shoes for children and crooked heels on shoes worn by adults, this being accomplished by reason of the fact that a flexible cushion is provided which will tend to effectively hold the heel bones in proper anchored position, the heel bones not having a tendency to slip or rotate within the heel of the shoe. 75

Changes in details may be made without departing from the spirit or the scope of this invention, but:

What I claim as new is:

1. In a shoe, a combination middle and inner sole, an outer sole, and a heel piece 85 inserted between the heel portions of said soles, said heel piece including a body of relatively stiff material and a pad of resilient material, said pad projecting through the body beyond the opposite faces thereof, 90 the combination middle and inner sole having a cavity in its lower face receiving the projecting upper end of the pad.

2. In a shoe, a combination middle and inner sole, an outer sole, and a heel piece 95 inserted between the heel portions of said soles, said heel piece including a body of relatively stiff material and a pad of resilient material, said pad projecting through the body beyond the opposite faces thereof, 100 the combination middle and inner sole having a cavity in its lower face receiving the projecting upper end of the pad, the cavity defining a relatively thin section of flexible material over the pad. 105

3. In a shoe, a combination middle and inner sole, an outer sole and a heel piece inserted between the heel portions of the combination middle and inner sole and the outer sole, said heel piece including a body of relatively stiff material and a pad of resilient material, the forward edge of the heel piece being beveled, said pad projecting through the body beyond the opposite faces thereof for engaging the inner faces of the combination middle and inner sole and the outer sole, the combination middle and inner sole having a cavity in its lower face receiving the projecting upper end of the pad, the combination middle and inner sole, outer sole and heel piece being all fastened together. 115 120 125
